(57) **CLAIM**

The ornamental design for a case for mobile phone, as shown and described.

DESCRIPTION

FIG. 1 is a front perspective view of a case for mobile phone showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The features shown in broken lines, and unshaded surfaces bound on all sides by broken lines, represent portions of the case for mobile phone that form no part of the claimed design.
